No. 611,266.

F. B. MORSE.

Patented Sept. 27, 1898.

SHOE.

(Application filed Sept. 10, 1897.)

(No Model.)

UNITED STATES PATENT OFFICE.

FRANK B. MORSE, OF HAVERHILL, MASSACHUSETTS.

SHOE.

SPECIFICATION forming part of Letters Patent No. 611,266, dated September 27, 1898.

Application filed September 10, 1897. Serial No. 651,180. (No model.)

To all whom it may concern:

Be it known that I, FRANK B. MORSE, a citizen of the United States, residing at Haverhill, in the county of Essex and State of Massachusetts, have invented certain new and useful Improvements in Shoes; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention seeks to so improve the construction of a shoe-upper that the shoe will fit closely to the ankle and will have all the flexibility and freedom of movement that is necessary for ease and comfort in walking, 20 bicycle-riding, and other forms of athletic exercise, while at the same time it will give the ankle a neat and slender appearance.

A further object of the invention is to economize in the quantity of leather necessary 25 to form the upper and thereby reduce the cost of the shoe without detracting from its quality.

With these objects in view the invention consists in providing the upper with an elastic gore in its side and with narrow tongues 30 rising from the base of the gore-opening, as illustrated in the accompanying drawings and hereinafter first fully described and then pointed out in the claim.

Shoes provided with elastic gores of various 35 shapes have been made heretofore and are well known. While they give free movement to the ankle, the unsupported goring soon loses its shape, and if of a poor quality of rubber it quickly stretches to such an extent as to 40 fail to hold the shoe. It has been attempted to overcome this defect by constructing the upper with a compound gore consisting of alternate strips of leather and elastic goring. This arrangement, however, is unsatisfactory 45 and objectionable because the leather strip passes over the ankle and although supporting it causes an irritation of the same during walking or other exercise. Furthermore, the leather strip by bearing directly on the ankle 50 renders the shoe uncomfortable to the wearer. All of these objections are overcome by my invention.

In the accompanying drawings, Figure 1 is a side elevation of a shoe embodying my invention. Fig. 2 is a horizontal section of the 55 same. Fig. 3 is a detail view of the quarter. Fig. 4 is an elevation of the inner side of the shoe, showing the lining and the elastic goring; and Fig. 5 is a view showing the form of the quarter when a facing is used.

In carrying out my invention I cut the rear and lower edges of the quarter A on the usual lines; but the front edge B thereof is cut on a line running decidedly in rear of the line usually followed by the front edge of the 65 quarter. To form the gore-opening, I cut a series of slits C, running from the top of the quarter downward to near the bottom of the same, thereby forming two or more slender tongues D, rising from the base of the gore-opening and terminating a short distance below the top of the same. The elastic webbing or goring E is cut in a single piece large enough to cover the entire gore-opening and is sewed to the edges of the same, the tongues 70 D being sewed flat against the outer face of the goring. The lining F is cut to follow the outline of the goring, except that it is formed with the upwardly-projecting points G, which serve to reinforce the tongues D at their bases. 75 When the shoe is properly fashioned, the top of the quarter will be rather narrow, so that when attached to the goring it will be spread somewhat, and consequently there will be a reaction or tendency of the quarter to hug 80 the ankle and thereby aid the goring to support the same. The elastic properties of the goring are not affected and free movement of the ankle is permitted. The tongues D 85 will fit against the front and rear sides of the ankle and will consequently brace the same without passing thereover. The tongues, being very narrow, impart a slender appearance to the ankle and at the same time serve to ornament the shoe. The goring being in a 90 continuous piece there are no seams on the inside of the shoe to press against and irritate the ankle, but it rests against a perfectly 95 smooth and easy surface.

When a facing is employed, the quarter is 100 cut without the usual front strip and the facing is secured at its lower end to the front corner of the quarter, as shown in Fig. 5.

The saving effected by my invention in the

quantity of leather used is obvious. The shoe has a neat and attractive appearance, and its wearer may take all desired exercise without any feeling of fatigue or any weakening or irritation of the ankle. The shoe is laced or otherwise fastened in the usual manner.

It must be understood that I make no broad claim to a combined leather and elastic gore, my invention residing in providing two or 10 more narrow leather tongues rising from the base of the gore-opening and on the outside of a single continuous elastic gore. These tongues serve to hold the goring close around the ankle, so that the ankle will be braced and the shoe caused to fit the ankle perfectly, while at the same time free movement of 15 the ankle is permitted without any irritation thereof. Furthermore, the goring being nearly coextensive with the quarter a great 20 saving of leather is effected.

Having thus described my invention, what I claim, and desire to secure by Letters Patent, is—

A shoe having its quarter provided with a gore-opening and having a series of slender 25 tongues rising from the base of said opening, an elastic goring extending over the entire opening and sewed to the side edges of the same, the tongues being sewed to the outside of the said goring, and a shoe-lining sewed to 30 the edge of the said goring and having points on its upper edge sewed to and reinforcing the bases of the tongues.

In testimony whereof I affix my signature in presence of two witnesses.

FRANK B. MORSE.
